UNITED STATES PATENT OFFICE

171,034

SURGICAL LIGHTING FIXTURE

Ernest H. Greppin, Brighton, N. Y., assignor to
Wilmot Castle Company, Rochester, N. Y., a
corporation of New York

Application August 19, 1952, Serial No. 21,110

Term of patent 14 years

(Cl. D48—20)

To all whom it may concern:

Be it known that I, Ernest H. Greppin, a citizen of the United States of America and resident of Brighton, in the county of Monroe and State of New York, have invented a new, original, and ornamental Design for a Surgical Lighting Fixture, of which the following is a specification, reference being had to the accompanying drawings forming part hereof.

Fig. 1 is a perspective view of a surgical lighting fixture, showing the new design;

Fig. 2 is a perspective view of the same, viewed from a different angle; and

Fig. 3 is a perspective view of the same, viewed from still another angle.

I claim:

The ornamental design for a surgical lighting fixture, substantially as shown.

ERNEST H. GREPPIN.
